United States Patent Office

Des. 219,144
Patented Nov. 10, 1970

219,144

RECOIL PAD

Russell N. Hofmeister, Waseca, Minn., assignor to
Herter's, Inc., Waseca, Minn., a corporation of Minnesota

Filed Nov. 6, 1968, Ser. No. 14,331

Term of patent 14 years

Int. Cl. D22—02

U.S. Cl. D22—9

FIG. 1 is a front elevation view.

FIG. 2 is a side elevation view.

FIG. 3 is a rear elevation view.

FIG. 4 is a top plan view.

FIG. 5 is a bottom plan view.

FIG. 6 is a sectional view on an enlarged scale taken on a line 6—6 of FIG. 2, being fragmentarily shown for convenience of illustration.

The side opposite that shown in FIG. 2 is identical to that seen in FIG. 2.

I claim:

The ornamental design for a recoil pad, as shown and described.
